MIXING NOZZLE

Elbert O. Sowerwine, Jr., Woodbury, N. J., assignor to Socony-Vacuum Oil Company, Incorporated, a corporation of New York

Application May 20, 1943, Serial No. 487,713

4 Claims. (Cl. 252—359)

This invention relates to a nozzle for mixing and ejecting colloidal solutions capable of setting to solid or semi-solid states such as gels. More particularly, the invention contemplates the formation and ejection of colloidal solutions which set to form inorganic oxide hydrogels.

In the copending application Serial No. 461,454, filed October 9, 1942, by Milton M. Marisic, a process is described for forming hard, spheroidal beads of inorganic oxides by injecting solutions which will gel in a predetermined time into a liquid immiscible therewith and permitting gelation of resultant globules of the solution in the immiscible liquid. The resultant globules of hydrogel are then removed and processed to form the desired final product.

In operation of such processes, difficulties arise due to gelation of small portions of the solution within the mixing nozzle forming deposits of gel which gradually build up. In the said Marisic application, it is proposed to avoid this difficulty by means of a rotary cleaning member within the nozzle. Deposits can also be avoided by high velocity flow within the nozzle. The first means includes a moving member within the nozzle which occupies space and requires packing at the bearings; while high velocity flow impairs the capacity of the device to produce uniformly sized globules.

I have now devised a mixing nozzle of novel structure which is self-cleaning in operation but which contains no moving parts inside the nozzle itself. These useful characteristics are achieved by forming the walls defining the nozzle chamber of a resilient material such as rubber and providing means to flex the resilient walls at frequent intervals or continuously. According to my invention, the resilient walled chamber has an external cross-section other than a circle, that is, at least one external cross-sectional dimension is greater than one other such dimension. The flexing means is constituted by a member about the resilient chamber and co-axial therewith which may be rotated about the common axis. The internal cross-section of the outer member is also other than a circle and has a smallest internal cross-sectional dimension larger than the least dimension of the chamber but less than the greatest dimension of the chamber. Thus, rotation of the outer member about the chamber causes the latter to be deformed, flexing its walls and thereby breaking loose any gel which may have formed thereon.

The outer member may also be resilient, but it is preferred that it be rigid in order that all

deformation caused shall be in the wall of the mixing chamber.

The objects and advantages of my invention will be further understood by consideration of preferred forms thereof described below in connection with the annexed drawing wherein:

Figure 1 is a diagrammatic illustration of a preferred embodiment of my invention; and

Figures 2, 3 and 4 are cross-sections through typical nozzle forms according to the invention.

Referring specifically to Figure 1, the apparatus comprises a vessel 10 containing a column of oil or other liquid immiscible with the sol and a layer of water below that column. Water is admitted by pipe 11 to the bottom of vessel 10 and withdrawn by pipe 12 to carry off spheroidal gel particles formed in the vessel as described below. Reactant solutions to form a sol which will gel in the time required for it to fall through 15 the oil are admitted by pipes 13 and 14 from metering pumps 15 and 16 to a mixing nozzle 17. The nozzle 17 is a flexible walled tube in which the reactant solutions are rapidly and intimately mixed to form the sol. The nozzle 20 may, if desired, be reinforced, as by metal rods 25 or the like embedded therein.

The nozzle 17 is of a shape other than circular as shown in Figures 2, 3 and 4, thus having at least one external cross-sectional dimension substantially greater than another such dimension. About the flexible tubular nozzle 17 is a member 18 adapted to deform nozzle 17 when rotated about their common axis. The member 18 is preferably rigid, being advantageously a metal tube of similar cross-section to that of nozzle 17. It may, however, be formed of flexible material. As shown in Figures 2, 3 and 4 the smallest internal cross-sectional dimension of the member 18 is greater than the smallest but 30 less than the greatest external cross-sectional dimension of nozzle 17.

Means are provided to rotate member 18 about its axis. For example, a ring gear 19 may be secured to the member 18 and mounted on bearings 20 carried by a spider 21 affixed to the walls of the vessel 10. A pinion 22, driven by motor 23, is provided to drive gear 19 and thus rotate the member 18 with respect to nozzle 17. In this manner, any substantial amount of solid or 45 semi-solid gel phase formed in the nozzle 17 will be broken from the walls thereof when the latter are deformed, thus preventing accumulation of such gel in the nozzle.

In a typical operation, sodium silicate solution containing 105 grams of SiO_2 per liter is

prepared by diluting "N" brand of sodium silicate (28.7% SiO_2 , 8.9% Na_2O). This solution is mixed with a second solution containing 34.10 grams $\text{Al}_2(\text{SO}_4)_3$ and 25.05 grams of H_2SO_4 per liter at the rate of 1.00 volume of the former solution to 0.760 volume of the latter in mixing nozzle 17. The resultant colloidal solution is introduced into the top of a column of gas oil of eight feet in depth. The globules of oil fall through the oil and gel before passing into the 5 layer of water located beneath the oil. The gel in the globular form is conducted out of the bottom of the column in a stream of water and, on removal from the water, is washed with water and NH_4Cl solution, to remove soluble salts and 10 replace zeolitically held sodium ions by ammonium ions which are capable of being driven off as ammonia gas by heat. The gel is dried slowly and uniformly at 180° F. until shrinkage is substantially complete and the drying is then 15 continued at gradually increasing temperatures up to about 1050° F. at which temperature it is maintained for two hours. The resultant product is in the form of hard, "glassy" spheroidal pellets which have excellent properties as cracking catalyst for the conversion of gas oil and 20 the like to gasoline.

I claim:

1. In a nozzle for intimately mixing and ejecting colloidal solutions which set to form inorganic oxide hydrogels, the combination of a rigid tube having internal cross-sectional dimensions differing substantially from each other, a resilient tube having external cross-sectional dimensions differing substantially from each other, the greatest 30 external said dimension of said resilient tube being less than the greatest internal said dimension of said rigid tube but greater than the least 35 internal said dimension of said rigid tube, said resilient tube being at least partially within said 40 rigid tube and substantially coaxial therewith,

and means to rotate said rigid tube with respect to said resilient tube.

2. In a nozzle for intimately mixing and ejecting colloidal solutions which set to form inorganic oxide hydrogels, the combination of a resilient tube having external cross-sectional dimensions differing substantially from each other, a member about and substantially coaxial with 5 said resilient tube having internal cross-sectional dimensions differing substantially from each other, the greatest external said dimension of said tube being less than the greatest internal said dimension of said member but greater than the least internal said dimension of said member, and 10 means to rotate said member with respect to said tube.

3. In a nozzle for intimately mixing and ejecting colloidal solutions which set to form inorganic oxide hydrogels, the combination of an elliptical rubber tube, an elliptical metal tube about and 15 substantially co-axial with said rubber tube, the major axis of said rubber tube being less than the major axis of said metal tube but greater than the minor axis of said metal tube, means to rotate said metal tube about the rubber tube and 20 means to feed fluids to be mixed to said rubber tube.

4. In a nozzle for intimately mixing and ejecting colloidal solutions which set to form inorganic oxide hydrogels, the combination of a rubber tube having external cross-sectional dimensions differing substantially from each other, a metal tube about and substantially co-axial with said rubber tube, the greatest external cross-sectional dimension of said rubber tube being less than the greatest internal cross-sectional dimension of said metal tube but greater than the least internal said dimension of said metal tube and 25 means to rotate said metal tube with respect to said rubber tube.
